UNITED STATES PATENT OFFICE.

WILLIAM E. HATHEWAY, OF BRIDGEPORT, CONNECTICUT.

BRASSIÈRE HOOK.

Application filed April 6, 1922. Serial No. 550,144.

To all whom it may concern:

Be it known that I, WILLIAM E. HATHEWAY, citizen of the United States, residing at Bridgeport, in the county of Fairfield and State of Connecticut, have invented certain new and useful Improvements in Brassière Hooks; and I do hereby declare the following to be a full, clear, and exact description of the invention, such as will enable others skilled in the art to which it appertains to make and use the same.

This invention relates to brassière hooks used with corset covers or brassières, and is adapted for properly holding a brassière in position in connection with corset steels or lacings front or back, and it consists in making the slot for the reception of the corset stud of such an irregular shape that the hook cannot become accidentally disengaged.

In the accompanying drawings wherein the same figures and letters of reference indicate like parts throughout the several views;

Figure 1 represents a detail view of the hook adapted for either front or back laced corsets, also sectional view of a corset stud in the normal position it will occupy when the hook is engaged therewith;

Figure 2 is a broken view of corset steels connected by the usual clasp, and the hook engaging the stud;

Figure 3 is a view looking in the direction of arrow *a* of Figure 2, also a broken view of the hook supporting tape;

Figure 4 is a detail view of a hook minus the offset feature for engaging the lacing;

Figure 5 is a view of the hook, broken view of its supporting tape, broken view of the lacing engaged by the offset portion of the hook;

Figure 6 is a view of the hook tilted to one side, and broken view of its supporting tape, and

Figures 7, 8, and 9, are broken views of the hook showing different modified forms of the irregularly shaped slots for corset studs.

The hook consists of the metal base 1 having, Figures 1, 2, 4, 5, and 6, the openings 2 and 3 to receive the brassière supporting tape 4. 5 is the usual opening for the head 6 of the corset stud 7 when the corset steels 8 and 9 are connected together by the clasp 10, Figure 2.

In Figures 1, 2, 4, 5, and 6, the irregular shaped stud slot 11 radiates from the large

opening 5, terminating in a well defined curve 11^a at the bottom of the hook. The slot is so shaped that the stud 7 will normally lie at the lowest point of the curve, Figure 1, and at one side of projection 12, so that, any downward movement of the hook, due to bending over of the wearer, will engage the edge 13 with the stud and cause the hook to swing to one side, Figure 6, and thus prevent the hook entering that portion of the slot leading directly into the opening 5, as would be the case if the slot led in a straight line from said opening.

To release the hook, it is necessary to manually swing the hook in the opposite direction far enough for the projection or tongue 12 to pass the stud and align it with that part of the slot leading directly into the large opening 5, when a slight downward pressure will release it.

To utilize the hook also for engagement with the corset lacings 14, Figure 5, the central portion 1^a is offset to provide the required receptacle to admit the lacings. This offset, Figure 3, will lie in such proximity to the corset steel carrying the studs so that any undue movement on the part of the opposite steel that would tend to unfasten the clasp 10 would be counteracted by the engagement of said steel with the hook.

In the modified form of the slot shown in Figures 7 to 9 inclusive, the same idea of irregular formation to prevent accidental disengagement of the hook is carried out. To avoid confusion with the slots shown in the preceding figures, these modified shaped slots will be designated by letters of reference as follows:

In Figure 7, the slot *b* is staggered to such an extent that when the stud is at the lowest point *c*, it would be prevented by the several angles of the slot from reaching the opening 5. The same security is met in the slot *d*, Figure 8, when the stud is normally located at *e*. In Figure 9, the point *f* being the normal position of the slot *g* for the stud, any downward movement of the hook would naturally bring the stud into the recess *h*, rather than into that part of the slot leading into the opening 5.

It is quite evident that the irregular shape of the slot can be greatly varied to suit the shape and size of the hook and give the necessary strength. Therefore, I do not wish to be held to any particular shape of the slot so long as the slot leads out from the

large opening in an irregular path. I employ the term "irregular slot" to mean any deviation from a radial line drawn from the center of the opening 5 that will effectually prevent accidental disengagement of the hook from the stud, and this can best be effected by a slot having lateral offsets.

Having thus described my invention what I claim is:—

10 A brassière hook comprising a base having

an opening to receive the head of a corset stud and an irregularly shaped slot for the reception of the body of the stud leading therefrom and narrower than said opening and so shaped as to effectually prevent accidental detachment of the hook from the stud, and a portion of said base offset for the reception of the corset lacing.

15 In testimony whereof I affix my signature.

WILLIAM E. HATHEWAY.
